UNITED STATES PATENT OFFICE.

RODERICK G. STEVENS, OF CHICAGO, ILLINOIS.

MAILING-FOLDER.

No. 892,461.

Specification of Letters Patent.

Patented July 7, 1908.

Application filed August 9, 1907. Serial No. 387,891.

To all whom it may concern:

Be it known that I, RODERICK G. STEVENS, a citizen of the United States, residing at Chicago, in the county of Cook and State of Illinois, have invented a certain new and useful Improvement in Mailing-Folders, of which the following is a specification.

My invention relates to mailing devices more particularly mailing folders employed for advertising purposes or under any circumstances where a reply is desired by the sender.

The preferred form of my invention is illustrated in the accompanying drawings, in which:

Figure 1 is a perspective view showing in full lines the device folded and in condition ready for mailing by the sender. The dotted lines indicate the leaves partially open. Fig. 2 is a transverse sectional view of the folded device, the section being taken on the line 2—2, Fig. 1. Fig. 3 is a perspective view of the inside of the folder showing the insert in position. Fig. 4 is a face view of the insert and shows how a single writing of the address serves both for the going folder and the returning insert. Fig. 5 is a fragmentary perspective view showing a modification in which tongues instead of a strip are cut from the main leaf for holding the insert in position.

The different portions are indicated by similar reference characters throughout the views.

In the form shown in Figs. 1 to 4 inclusive, the folder consists of three leaves, the main leaf *a*, the inner leaf *b* and the outer leaf *c*. Although the folder in its best form has three leaves, one on each side of the main leaf, more might be employed and two 40 is the minimum number. The main leaf has two slits *a'*, *a''*, which are preferably parallel and of an extent sufficient to afford the requisite area for a name and address. As a result of the presence of the slits a strip *a³* is formed in the main leaf.

The insert *d* is rectangular in outline and has spaces such as *d'*, *d''*, *d³*, for a name and address (see Fig. 1). By preference these spaces are properly designated by lines or 50 words or both, as illustrated. Said insert is of approximately the same height as the main leaf *a* and of approximately the same length as the slits *a'*, *a''*. This serves to hold the insert definitely in place so that the 55 name and address will appear in front of the opening in the main leaf.

A gummed flap or "sticker" *e* is the preferred means for fastening the leaves in folded position.

Operation: When the folder is open, the insert *d* is put in place by passing it along the back of the main leaf *a*, then down in front of the strip *a³*, then behind the lower portion of the main leaf until the upper and lower edges of the insert are even with the upper and lower edges of said leaf. The spaces *d'*, *d''* and *d³* are then visible from the front of leaf *a* through the opening therein as shown in Fig. 1. The leaves *b* and *c* are then folded up behind the insert and secured by the fastening device *e*.

To illustrate an advantageous use of this device let it be assumed that a publisher John Doe & Company wishes to sell a book and wishes to get replies from possible buyers 75 as to whether they would like to see the book or whether they would like to have a representative call. On the inside of one or all of the leaves of the folder the publisher will print reading matter descriptive of the book 80 which he wishes to sell. As an insert *d* he will employ a postal card either with or without a one cent stamp thereon. On the stamp side of this postal card he will put his own name and address John Doe & Company, 358 Dearborn St., Chicago, Ills. as shown in Fig. 3. On the opposite side of the insert, shown in Fig. 4, the publisher will print reading matter so worded that he will become cognizant of the desires of the prospective buyer without other labor on the part of the prospective buyer than the placing of a check mark or other suitable indication in one or more suitably designated spaces on the reading matter side of the 95 postal card. The publisher will in the spaces *d'*, *d''*, *d³* write in long hand or typewriting the name and address of the prospective buyer for example: Richard Roe, 172 North ave., Denver, Colo. The publisher will 100 then place the insert in the folder in such position that his own address comes upon the inside of the folder as shown in Fig. 3 and the address of the prospective buyer is visible through the front of the main leaf *a* 105 as indicated in Fig. 1. The leaves are then folded together and the flap *e* closed so as to hold the device folded but with the ends open. When thus folded and secured the insert is held fast and can not become dislodged except through the breaking of the strip *a³*. As the strip is protected by being

on the inside there is practically no possibility of the separation of the two parts while in the mail or in transit from the publisher to the buyer. When the buyer receives the folder he opens it and first refers to the reading matter and then if he desires to receive a copy of the book or have a representative call he so indicates upon the postal card and mails the card. As the publisher's address is already upon the card the buyer is saved the trouble of writing it. He is also saved the trouble of writing his own name and address for it has already been written by the publisher and has served to direct the folder to the buyer.

It will be seen that a device embodying this invention has great advantages; first, the entire folder and insert may be mailed for the cost of one cent postage; second, practically no labor is required of the prospective buyer; third, there is no possibility of the purchaser sending back the card without his proper and complete name and address; fourth, the folder can be used over again in case it is returned without being delivered. These and other advantages will be readily apparent to those skilled in the art.

Of course this device may be employed in a great variety of ways and in fact it is applicable to practically any circumstance where a reply is desired.

Some modifications may be made in the manner of constructing the strip a^3 , for example, instead of the strip extending entirely across the address opening as in the form of device shown in Figs. 1 to 4, it may extend only partially across from each end, thereby forming tongues f as shown in Fig. 5.

What I claim as new and desire to secure by Letters Patent is:

1. A mailing folder having leaves one of which is cut for engaging an insert and exposing a portion thereof to view when the folder is folded, the cut portion of the folder having means adapted to engage the insert to prevent lateral displacement thereof, and the folds of the folder being at a distance apart slightly greater than the height of the insert whereby they are adapted to prevent vertical displacement of the insert.

2. A mailing folder having a plurality of leaves folded along parallel lines transverse to the lateral edges of the folder, one of the leaves having a sight aperture formed therein by making parallel slits in said leaf, which slits are transverse to the lateral edges of said folder, and an insert of a height slightly less than the slitted leaf of the folder and adapted to be held from vertical displacement by the

leaves adjoining the slitted leaf, a portion of said insert lying in front of the sight aperture in said slitted leaf in order to expose a portion of said insert and prevent lateral displacement of the insert relatively to the folder.

3. In a device of the class described, an open-end folder consisting of a sheet of paper having a plurality of leaves folded along parallel lines transverse to the lateral edges of the folder, one of the leaves having a sight aperture formed therein by making parallel slits in said leaf, which slits are transverse to the lateral edges of the folder, and an insert of a height slightly less than, but practically equal to the height of the leaf which has the sight aperture, said insert being engaged by portions of said apertured leaf at the ends of the sight aperture therein, whereby lateral displacement of the insert within the open-end folder is prevented.

4. An open-end mailing folder consisting of a main leaf having a strip formed therein, said strip extending transversely to the lateral edges of the folder and being formed by slitting the main leaf, and said main leaf having other leaves integral therewith and adapted to fold thereon along folding lines transverse to the lateral edges of the folder; and an insert of substantially the same height as the main leaf and adapted to be folded within the folder adjacent to the main leaf and adapted to have a portion of its surface exposed in front of said strip; and the exposed portion of said insert having a space adapted to receive the name and address.

5. A mailing folder consisting of a main leaf having a transverse strip formed therein by slitting the main leaf and adapted to engage an insert to prevent lateral displacement thereof and said main leaf having other leaves integral therewith and adapted to fold thereon along folds transverse to the lateral edges of the folder; an insert of substantially the same height as the main leaf adapted to be folded within the folder adjacent to the main leaf and adapted to have a portion of its surface exposed in front of said strip; and a flap located at one of the edges of one of the leaves for holding the leaves of the folder together, the ends of the folder thereby remaining open.

6. A mailing folder folding upon parallel creases whereby the ends of the folder remain open when the folder is folded, said folder having a main leaf having cuts therein forming a strip extending substantially parallel to said creases, said strip being adapted to pass behind an insert to thereby prevent movement of said insert lengthwise of said strip and simultaneously exhibit a portion of said insert for the purposes described.

In witness whereof, I have hereunto subscribed my name in the presence of two witnesses.

RODERICK G. STEVENS.
